TYPEWRITING MACHINE

George James Munson Pilgrim, Thornton Heath, Surrey, England, assignor to Remington Type-writer Company, Ilion, N. Y., a corporation of New York

Application July 24, 1930, Serial No. 470,320
In Great Britain January 30, 1930

30 Claims. (Cl. 197—128)

My invention relates to typewriting or like machines and more particularly to means for aiding in quickly introducing and collating work sheets in the machine and for simultaneously feeding 5 such collated sheets if desired.

The main objects of my invention, generally stated, are to provide comparatively simple yet highly efficient mechanism of the character specified which may be employed in various kinds 10 of billing operations; by which various features or devices of the construction may be automatically controlled; in which an improved line indicating device is automatically shifted into and out of position for use; in which various work 15 sheets may be rapidly introduced into the machine and quickly adjusted therein in proper correlation with another previously introduced sheet; and by which various work sheets may be introduced rearwardly into the machine from in front of and beneath the platen after another or other previously introduced sheets have been 20 inserted into the machine from the rear of and beneath the platen.

To the above and other ends which will herein- 25 after appear my invention consists in the features of construction, arrangements of parts and combinations of devices set forth in the following description and particularly pointed out in the appended claims.

In the accompanying drawings wherein like reference characters indicate corresponding parts in the different views:—

Fig. 1 is a vertical, fore and aft, central, sectional view taken on the line 1—1 of Fig. 6 and 30 looking in the direction of the arrows at said line. This view shows the carriage of a typewriting machine mounted in place and equipped with the devices of my invention; the parts being shown conditioned ready for writing.

Fig. 2 is a like view of the same with parts 35 omitted and showing the machine conditioned to receive a rearwardly introduced work sheet.

Fig. 3 is an end elevation of the carriage, showing 40 the parts as they appear after the bill sheet has been introduced into the machine with the parts in the position they occupy just before the feed rollers are pressed and locked in effective position.

Fig. 4 is a like view with the parts conditioned 45 as they appear in Fig. 2 but showing the devices at the other end of the platen.

Fig. 5 is a vertical, transverse, sectional view taken through the carriage on the line 5—5 of Fig. 1 and looking in the direction of the arrows at said line.

Fig. 6 is a top plan view of the carriage.

Figs. 7, 8 and 9 are fragmentary, skeletonized, end views showing the parts differently disposed, and more particularly the line indicator, when the machine is conditioned as represented in 5 Figs. 1, 3 and 2 respectively.

Fig. 10 is a like view including additional parts and showing the parts disposed in an intermediate position between those positions which are indicated in Figs. 8 and 9.

The present invention was devised to attain 10 some of the same general ends as the construction disclosed in the patent to Frederick A. Hart, 1,650,351, dated Nov. 22, 1927, and may be regarded as an improvement thereon.

I have shown my invention in the present instance embodied in a Smith Premier typewriting machine in which the devices of my invention may be readily incorporated without materially modifying the existing structural features 20 of said machine. It will be understood that said machine is a front strike typewriting machine in which the platen is fixed against movement from printing position.

The frame of the machine includes a top plate 25 1 on which fixed carriage rails 2 and 3 are supported by brackets 4 in the usual manner. Said rails are provided with oppositely grooved race-ways to receive crossed bearing rollers 5 which also are received in race-ways in a cross bar 6 of 30 the carriage. In this manner the carriage is supported at the rear thereof for traveling movement from side to side of the machine over the top plate 1.

The carriage includes end bars 7 and 8 which 35 are secured to and project forward from the rear cross bar 6 and have bearing openings therein for the platen shaft 9 by which a cylindrical platen 10 is supported. The usual line spacing mechanism and finger wheels (not shown) are employed 40 for turning the platen.

A paper table 11 is supported in the rear of the platen to aid in directing forwardly introduced work sheets to the rear of and beneath the platen.

Forwardly extending arms 12, each of which 45 forms part of a bracket 13 or 14 fixed to the carriage in the usual manner, constitute means by which a supporting bar (not shown) for vertical totalizers of the computing mechanism is connected with the carriage.

Upwardly and rearwardly moving type bars, a fragmentary portion of one of which is shown at 50 15 in Fig. 1, strike against the front of the platen or the paper thereon. A line *a* in the different figures represents the printing line or a line with 55

which the bottom ends of the printed characters register. The type bars in moving to printing position coact with a type bar center guide 16 secured to the type bar segment 17.

5 A ribbon vibrator 18 is automatically operated to carry a ribbon 19 into the path of the types at each printing operation.

The construction thus far described constitutes part of the well known Smith Premier machine and to which the devices of my present invention are applied. A paper deflector 20 which is curved in cross section to conform substantially to the surface of the platen is arranged beneath the platen and is fixed at the rear edge portion thereof to brackets 21 provided with set screws 22 by which the deflector may be fixedly connected to a rock shaft 23. A rocking of this shaft is effective to move the deflector from the Fig. 1 to the Fig. 2 position and vice versa. The rock shaft 23 carries 10 a crank arm 24 at one end thereof which is fixedly connected to the shaft by a set screw 25, thus enabling the crank arm to be secured in different adjusted positions to the shaft. A forwardly projecting link 26 is pivoted at its rear end, as at 27, to the crank arm 24 in order to automatically effect a movement of the deflector down from the Fig. 1 to the Fig. 2 position and up again, as will 15 hereinlater more clearly appear.

In the present construction I provide a plurality 20 of flexible or resilient work sheet supporting and guiding bands 28, two being shown in the present instance. These bands are provided to cooperate with the platen 10 to aid in supporting, guiding and feeding one of the work sheets, L, to and 25 around the platen as such work sheet is introduced from the rear thereof. Each of these bands 28 is secured at its upper rear end by bolts 29 and nuts 30 to the upper horizontally disposed portion of the paper table 11. The bands 28 extend 30 from the attached ends thereof parallel with the paper table 11 and around and concentric with the platen and up in front of and above the platen where the free ends of the bands bear against a cross bar 31 fixed to the carriage and extending 35 from side-to-side thereof above the platen. These bands are slightly resilient and bear against the platen with sufficient force to snugly maintain a work sheet L which is introduced into the machine from the rear of the platen and between 40 said bands and platen, in contact with the platen and cause the sheet to be effectively fed therewith when the platen is rotated.

The cross bar 31 is secured to the carriage by bracket arms 32 carried thereby, said bracket 45 arms being secured by set screws 33 to a cross rod 34 attached at its ends to the end plates 7 and 8 of the carriage. The cross bar 31 also constitutes a support for a second paper table 35, the front 50 face of which is maintained substantially tangential to the platen at the front portion thereof. This paper table constitutes a support for a work sheet B that is introduced into the machine from in front of the platen and is directed downwardly and rearwardly beneath the platen to the deflector 55 20, as indicated in Figs. 1 and 2.

In order to facilitate such an introduction of the sheet B into the machine, I have provided a second deflector plate 37 that is automatically moved from the ineffective position shown in 60 Fig. 1, to the effective position shown in Fig. 2, where the lower end of the deflector 37 is moved into cooperative relation with the deflector 20 to practically form a continuation thereof for directing the lower end of the work sheet B into 65 the machine past the type guide and ribbon vibra-

tor and into the channel 38 between the deflector 20 and the platen. In this movement of the deflector 37 to and from effective position, it moves past the printing line and must necessarily be moved from its effective position, shown in Fig. 2, to the ineffective position shown in Fig. 1, before the type bars can reach the printing position. This operation of the deflector 37 is automatically controlled, as will hereinlater more clearly appear.

10 It will be understood that a carbon sheet C, preferably substantially coextensive with the work sheet L is simultaneously introduced into the machine therewith and is employed for making a manifold copy of the work written on the work sheet B. If desired, a carbon sheet coextensive in size with the bill sheet B may be introduced and withdrawn with the latter instead of employing the carbon sheet C in the manner indicated.

15 In order to facilitate a proper positioning of both the ledger sheet L and bill sheet B in the machine, I have provided a line indicator which is in the nature of a thin flat sheet metal strip 39 that extends longitudinally throughout the length of the platen and is connected at its ends to depending portions 40 of two arms 41 and 42. These arms at their forward ends are secured by set screws 43 to a rock shaft 44 that extends across the carriage from side-to-side thereof and is supported in bracket arms 45 fixed to the carriage. 20 It will be understood, therefore, that the line indicator 39 receives a direct up and down motion to and from indicating position around the center of the shaft 44, the line indicator being shown in its indicating position in register with the printing line a in Fig. 8, and in the lowered, ineffective, position in Fig. 7. Means are provided for automatically controlling the line indicator 39, as will hereinlater more clearly appear.

25 I have provided means whereby the only paper feed rollers, 46, which are brought into cooperation with the platen are mounted for movement from the effective position represented in Fig. 1, to the ineffective position, indicated in Fig. 2 and vice versa. It will be observed that when the feed 30 rollers 46 are in the effective position they are disposed above the printing line a and are adapted to coact with the work sheets B and L and the interposed carbon sheet C, only above the printing line. As clearly shown in Figs. 5 and 6 the feed rollers 46 are mounted on a supporting shaft or spindle 47, each end of which receives a bearing in an arm 48 provided at its forward end with a hub 49 supported on a rock shaft 53. Each arm 45 carries a pin 50 by which one end of a coiled spring 51 is connected to the companion arm 48, the opposite end of said spring being anchored to a collar 52 secured by a set screw 52a to the rock shaft 53. Each hub 49 is slabbed off at one side 55 thereof, as indicated at 54, to provide a contact face for cooperation with a corresponding slabbed off portion or contact face 55 of a collar 56 secured by set screws 57 to the rock shaft 53. There is a slight lost motion provided between the contact face 55 of each collar 56 and the contact face 54 of the associated hub 49 with which it 60 coacts. The construction is such that each arm 48 is provided with an individual spring 51 which exerts its individual force on the companion arm 48, as will presently appear, and that the effective 65 force of each of said springs may be varied by a rotative adjustment of the companion collar 52 to different set positions around the shaft 53. When the shaft 53 is rocked, both arms 48 and the springs 51 will turn bodily therewith, and but 70

75

a slight spring pressure is exerted by each of the springs 51. When, however, the shaft 53 is rocked a sufficient distance to bring the feed rollers 46 against and arrest them by the platen while a continued motion is given to the shaft, the effect will be to turn the collars 52 while the arms 48 are maintained fixed against movement, thus winding, stressing or tensioning the springs 51 and applying the force thereof against the arms 48 and the feed rollers 46 carried thereby. The extent of this continued motion of the shaft 53 after the feed rollers are brought to bear against the platen, corresponds to the extent of lost motion provided for between the collars 56 and the hubs 49. This is sufficient, however, to effectively tension or stress the springs 51 and cause them to exert sufficient pressure on the feed rollers to maintain the latter against the work sheets with sufficient force to effectively feed such sheets when the platen is turned.

Fig. 3 represents the positions of the parts when the feed rollers 46 have been brought to bear against the work sheets without tensioning the springs 51. At this time the feed rollers bear against said work sheets wholly by the weight of the parts, free from any pressure of the springs 51. This is in order that the ledger or bill sheet, and more particularly the latter, may be adjusted relatively to the line indicator while the sheet is held by the feed rollers 46 in its position of adjustment, but without sufficient pressure to interfere with the adjustment of the sheet. When the work sheets have been properly adjusted and correlated, the rock shaft 53 is given a further rocking motion to tension the springs 51 and effectively apply a feeding pressure to the feed rolls 46. Means are provided for locking the rock shaft at the end of this movement by which the springs are tensioned, in order to prevent a return of the rock shaft under the reaction of said springs. Such locking means and the means for controlling the rock shaft 53, as well as other of the devices previously described, will now be referred to.

The rock shaft 53 constitutes the main actuating shaft by which the various devices of my invention, including the feed rollers 46, the bottom deflector 20, the line indicator 39 and the front deflector 37, are controlled. This shaft 53 is mounted at its ends in bracket plates 58 and 59 secured to the carriage frame, and near the right-hand end thereof said shaft is provided with a crank arm 60 that terminates in a finger piece 61 by which the shaft may be actuated. When the arm 60 is swung forward to the Fig. 2 position, the parts will remain in such position with the feed rollers 46 thrown off and maintained in the ineffective position giving free access to the front of the platen for the introduction of a bill sheet B and when desired, the accompanying carbon sheet. When the arm 60 is turned rearward to the Fig. 3 position, the weight of the parts alone will maintain the feed rollers 46 against the work sheets on the platen, free from pressure of the springs 51. When, however, the arm 60 is further depressed to the Fig. 1 position, this results by the further turning of the rock shaft 53 in tensioning the spring 51 and applying the effective force thereof on the feed rollers 46. In order to lock or latch the finger piece 61 and the rock shaft 53 against the reaction of the springs 51, and maintain the force thereof against the feed rollers, I have provided a latching means which will now be described.

Pivoted at 62 on the outer side of the arm 60

is an angular or bell crank lever 63 provided at the end of one of its arms with a finger piece 64, as best shown in Figs. 2 and 3. The other arm 63^a of the lever 63 has a locking pawl or latch 65 pivoted thereto at 66, said latch having a hook-like engaging end 67. Extending laterally from the member 65 are two lugs or stops 68 and 69 that are on opposite sides of and coact with the arm 63^a to limit the motion of the latch relatively to said arm. A leaf spring 70 is fixed at one end by screws 71 to the lever 63 and bears at its free end against the lug 69 to normally maintain the latch member related to the arm 63^a as shown in Fig. 2. Referring more particularly to Figs. 5 and 6, it will be seen that a coiled spring 72 surrounds the pivot 62 by which the lever 63 is mounted on the crank arm 60, the other end of said spring being fixed to the lever 63, as indicated at 75. The force of this spring is therefore exerted to turn the lever 63 in an anti-clockwise direction (as the parts are shown in Fig. 3) relatively to the arm 60. However, the extent of this relative movement of the lever 63 is limited by a pin 74 carried by the arm 60 passing into a slot 76 in said lever 63. With the aid of this construction a depression of the finger piece 61 from the Fig. 3 to the Fig. 1 position will result in tensioning the springs 51 of the feed rollers and in maintaining said pressure on the feed rollers so long as the finger piece 61 is maintained depressed by the operator. As soon, however, as the operator releases pressure on the key 61 the pressure of the springs 51 will be released. When the operator desires to maintain indefinitely the force of the springs 51 on the feed rollers, it is merely necessary to depress the finger piece 64 from the Fig. 3 to the Fig. 1 position. This will result in moving the crank arm 60 down through the pin and slot connection 74, 76, after the force of the spring 72 is overcome. The effect of thus moving the crank arm 60 is to tension the springs 51 exactly as such result is effected by depressing the key 61. In depressing the key 64 from the Fig. 3 to the Fig. 1 position the lower end portion of the latch 65 is brought to bear against the front flat face of a part 77 of the frame of the carriage. The effect of this is to cause a slight displacement of the latch 65 around its pivot 66 and against the force of the spring 70. As soon as the bill of the hook-like end 67 of the latch passes below the lower edge of the member 77, the spring 70 becomes effective to turn the latch 65 on its pivot 66 to engaging position, shown in Fig. 1, and the parts will remain locked in this position, the reactive force of the springs 51 holding the latch engaged under the part 77.

When it is desired to release the latch 65, it is merely necessary to press down on the key 61. The effect of this is to release the locked latch from the reactive force of the springs 51. The spring 72 then becomes effective to move the latch on its pivot 66 and withdraw the hook-like member of the latch from beneath the coacting locking member 77. The operator will then release the depressed key 61 and the parts will return to the Fig. 3 position, releasing the rollers from a spring pressure.

In addition to controlling the feed rollers in the manner described, the finger piece 61 also controls the movement of the bottom deflector 20 from the Fig. 1 to the Fig. 2 position and vice versa. Such means will now be described.

The link 26 (see Fig. 3) is a two part link, the members of which are united by a threaded connection at 78 and the front member is

slotted at 79 to receive the shank of a headed screw or pin 80 received at its threaded end in a tapped opening in a disk 81. This disk has a hub 82 (see Fig. 6) tapped to receive a set screw 83 by which the disk is secured to the rock shaft 53. Due to the pin and slot connection 80, 79 between the link 26 and the shaft 53, the deflector 20 will remain unaffected by the turning of the shaft 53 until just prior to the time that the arm 60, in swinging forward, reaches the Fig. 10 position. When such position has been reached, the pin 80 has reached the forward end of the slot 79 and has shifted the link 26 forward and moved the deflector 20 down away from the platen in order to create an enlarged, unobstructed, channel 38 between said deflector and the platen for the free passage of a rearwardly introduced work sheet B, and an accompanying carbon sheet if such be used instead of the carbon sheet C. It will be understood that the bands 28 hold the previously introduced ledger sheet L snug against the platen so that it offers no obstruction or obstacle to the ready backward introduction of the bill sheet B into position in the manner described.

As the finger piece 61 is moved rearward after the introduction of a sheet B, the pin 80 will be carried rearward enabling a spring 84 (Figs. 6 and 10) to elevate the deflector 20 to a position where it will bear lightly against the sheet B and press it lightly against the under sides of the metallic bands 28. The spring 84 surrounds the rock shaft 23 and is connected at one end to one of the brackets 21 and is connected at the other end to a fixed part 85 (see Figs. 1 and 10) of the carriage.

The rock shaft 53 also controls the movement of the line indicator 39 to and from effective, or indicating position, as will now be pointed out.

From an inspection of Fig. 4 it will be seen that one of the supporting arms, 41, for the line indicator 39 has one end of a contractile returning spring 86 connected thereto, at 87. The other end of this spring is connected to a pin 88 that projects from one side of the adjacent bracket plate 58. The force of this spring is exerted to move the arms 41 and 42 upward and bring the indicator 39 to the line indicating position, as shown in Figs. 3 and 8. The parts are arrested in their movement to such position by an adjustable screw stop 89 threaded into a fixed part of the carriage or bracket plate 58 and cooperating at its lower end with the arm 42, as shown in Fig. 8. The arm 42 carries an upwardly extending finger 90 and extends into the path of a cam 91 formed as a depending part of the crank arm 60. As the arm 60 is moved forward from the Fig. 8 to the Fig. 10 position, the cam 91 will be brought into engagement with the upper side of the arm 42, and the finger 90 which is formed thereon, to depress the line indicator 39 to the ineffective Fig. 10 position, and hold it in such position. As the indicator 39 reaches its lowermost position under control of the cam, the curved contact faces 92 on the cam reaches and coacts with the arm 42 and acts in the nature of a dwell to hold the indicator in its lowered position during the further forward motion of the arm 60. Such forward movement of the arm 60 is limited by a stop pin 93 on the hub 75 94 of the arm 60 coacting with a pin 95 pro-

jecting from the righthand bracket plate 59, as shown in Fig. 9.

The body portion of the arm 60 also is operative on the extreme end of the finger 90 of the arm 42 when said arm is moved backward and downward from the Fig. 8 to the Fig. 7 position, and at this time moves the indicator 39 from the indicating to the ineffective position out of the path of the types. This motion of the arm 60 takes place as said arm is moving from the Fig. 3 to the Fig. 1 position, to tension the springs 51 and apply the force thereof to the feed rollers 46, as hereinbefore described. Should the depression of the arm 60 just referred to be brought about by a depression of the key 64, then said springs 51 will be locked under tension and the line indicator will be held depressed until the latch 65 is released in the manner hereinbefore pointed out.

In addition to the foregoing operations brought about by a rocking of the shaft 53, or the arm 60 connected therewith, the movement of the front deflector 37 to and from effective position is brought about as will now be described.

As best shown in Figs. 2, 4 and 5 the upper edge 25 of the deflector 37 is bent around and secured to a shaft 96 supported at its ends for pivotal movement in bearings 97 in supporting arms 98 secured to a rock shaft 99. Fixedly connected to the rock shaft 96 near one end thereof is a crank 30 arm 100; a set screw 101 being employed to adjustably connect the hub of said crank arm to the shaft. The upper end of the crank arm 100 is provided with a headed screw or pin 102, the shank of which is received and works in an arcuate slot 103 in a link 104. This link is pivoted at 105 to a crank arm 106 mounted on the rock shaft 53. From the foregoing it will be understood that the deflector 37 is adapted to receive a bodily pivotal motion around the rock shaft 99, and also may receive a pivotal motion around the shaft or pivotal center 96 under control of the link 104. The construction and arrangement of the parts are such that the deflector 37 may receive a movement from the ineffective, normal position indicated in Fig. 1, where it rests on soft rubber buffers 37a on the shaft 99, to the position indicated in Fig. 10. When this last mentioned position has been reached, the pin 102 will have reached the rear end of the slot 103 in the link 104, thus from this point on controlling the motion of the deflector 37 around its pivotal center 96. A further movement of the deflector 37 from the Fig. 10 position to the Fig. 4, effective position, is a direct downward motion substantially tangential to the platen to clear the type guide 16 and ribbon vibrator 18 and bring the deflector 37 into cooperative relation with the bottom deflector 20, which at this time has been moved away from the platen, as indicated in Fig. 2. The parts at this time are conditioned to receive a rearwardly introduced bill sheet B into the machine and into the channel 38, as shown in said figure.

The following are the instrumentalities by which the supporting and controlling members 65 for the deflector 37 are actuated to effect the movements just described.

Referring more particularly to Fig. 1 it will be seen that the rock shaft 53 near the right hand end thereof is provided with a gear wheel 107 fixed to the shaft by means of set screws 108 (Fig. 6) that are received in tapped openings in the hub 109 of said gear wheel. The gear wheel 107 meshes with an idler 110 supported on a headed pivot screw 111 supported on the right-hand bracket 75

plate 59. This idler 110 meshes with a second idle pinion 112 supported on a pivot screw 112^a secured to the bracket plate 59. The idler 112 in turn meshes with a gear 113 secured to the shaft 99 on which the arms 98 are secured. It will be understood, therefore, that a rocking motion of the shaft 53 will, through the gearing 107, 110, 112 and 113 rock the shaft 99 and cause the arms 98 to be vibrated forward or back from the Fig. 1 to the Fig. 2 position and vice versa. The pivotal motion of the deflector 37 around its pivot 96 is controlled, as hereinbefore indicated, by the link 104 connected to the crank arm 106 operatively connected to the rock shaft 53.

15 The operative connection between the rock shaft 53 and the crank arm 106, by which the link 104 is controlled, is effected in the following manner.

The crank arm 106 is loosely mounted on the shaft 53 and is connected at 115 (see Figs. 4 and 6) to one end of a coiled spring 116 that surrounds the shaft 53 and is, at its opposite end, anchored to a collar 117 on the shaft 53. Said collar is secured by a set screw 118 to the shaft 53 and is capable of rotative adjustment on the shaft to different set positions to regulate the force of the spring on the arm 106. The force of the spring 116 normally maintains the arm 106 against a stop pin 119 projecting from the bracket 58, as shown in Fig. 10 and in dotted lines in Fig. 3. The force of the spring 116 is sufficient to hold the arm 106 in the normal position until the parts reach the Fig. 10 position. It will be observed that at this time the pin 102 has reached the rear end of the slot 103 and caused the deflector 37 to turn on its pivot 96 until the lower edge of said deflector reaches contact with the metallic bands 28, as shown in Fig. 10, and is held against further turning movement on the center 96. From this point on, and until the deflector 37 reaches the Figs. 2 and 4 position, the arm 100 positively moving down with the arms 98 will actuate the link 104 and arm 106 against the force of the spring 116. As the parts are brought to the Fig. 4 position, an adjustable screw stop 120, carried by one of the arms 98, will reach contactive engagement with the arm 100 and arrest and positively hold the deflector 37 against pivotal movement in one direction around the pivotal center 96, whereas the force of the spring 116 tends to hold the arm 100 against said stop 120, thus assuring the maintenance of the deflector 37 in proper relation to the platen and to the deflector 20.

55 As the arm 60 receives a rearward movement from the Fig. 2 position, the spring 116 will be effective to turn the arm 106 until the latter reaches the stop 119, as indicated in Fig. 10. This arrests the arm 106 and link 104, and in the further continued rearward and downward movement of the arm 60 to the Fig. 3 or Fig. 1 position, the pin 102 will move freely along the slot 103 while the deflector 37 is returned to its ineffective, Fig. 1, position.

65 By reason of the pivotal movement of the deflector 37 around two centers 99 and 96 and the controlling means described, said deflector may be moved from the ineffective position shown in Fig. 1, remote from the front face of the platen, rearward to the Fig. 10 position over the ribbon vibrator 18 and the type guide 16, and then receive a downward movement substantially tangential to the platen to the effective Fig. 2 position, without being interfered with by said type guide and vibrator and without the necessity of

moving the vibrator down in order that the deflector 37 may clear it.

From the foregoing description it will be understood that the forward movement of the arm 60 from the Fig. 1 to the Fig. 2 position results in moving the feed rollers 46 from the platen to an ineffective position remote from the platen, where the rollers give free access to the front of the platen for withdrawing the written bill sheet and introducing a new one after the ledger sheet has been removed and a new one has been introduced and accurately positioned. This same movement of the arm 60 also results in lowering the line indicator 39 to the ineffective position; in lowering the bottom deflector away from the platen to provide an enlarged, unobstructed channel 38, and in moving the front deflector 37 from an ineffective position to a position where it is brought into cooperative relation with the lowered deflector 20 to aid in effecting a backward introduction of a bill sheet B to and beneath the platen from in front thereof.

After the work sheets have been inserted and correlated with the aid of the line indicator, a rearward movement of the arm 60 to the Fig. 3 position will result in moving the feed rollers 46 against the work sheet, the weight of the parts holding the feed rollers against said sheets. This same movement of the arm 60 results in withdrawing the deflector 37 and moving it to ineffective position; in elevating the deflector 20 against the bill sheet and in elevating the line indicator 39 to indicating position. The bill sheet B at this time is held against accidental displacement by the feed rollers 46 that bear against it but not with sufficient force that said sheet cannot be given a final accurate adjustment with reference to the line indicator 39 which is in effective position at this time. This final adjustment of the bill sheet having been effected, the finger piece 64 is depressed to place the feed rollers 46 under the tension of the springs 51 and lock the parts in such condition. The depression of the finger piece 64 also results in forcing the line indicator 39 down to and in holding it in the ineffective position. The machine at this time is conditioned for writing and the operator may proceed with the writing, making a manifold copy on the ledger sheet L through the interposed carbon sheet C of all matter written on the bill sheet B, the latter of course being produced by the operation of the type faces on the usual inking ribbon 19 carried by the ribbon vibrator 18.

Suitable side edge gages for the ledger sheet L and for the bill sheet B may be provided. In the present instance I employ the usual side edge gage 121 (see Fig. 6) that is adjustable to different set positions along the paper table 11 and is in the nature of a plate or blade that extends up from the paper table 11 at substantially right angles thereto. This gage is adapted to coact with the left-hand side edge of the ledger sheet inserted in the rear of the platen. I also provide a side edge gage 122 (see Figs. 3 and 6) by extending an upright flange from the left-hand side of the paper table 35, the plane of the gage 122 being at substantially right angles to the plane of said paper table 35.

While I have referred herein to the ledger sheet L and the bill sheet B entered into the machine in a given manner it will be understood that such reference is by way of example only, and that the machine is capable of a wide range of uses both in billing operations and in other

fields, such as making out checks and simultaneously making manifold entries on a pay roll sheet which may remain in the machine. I do not deem it necessary to specifically describe the 5 various uses to which the machine may be put, it being sufficient in view of the present state of the art and the reference to the Hart patent, to state generally that the machine may be employed wherever a plurality of sheets are to be 10 introduced into and collated in the machine and written at a single operation.

From the foregoing description it will be understood that the feed rollers 46, bottom deflector 20, the front deflector 37, the line indicator 39 15 and the latch 65, etc., are all operated in timed relation one to another under control of a single finger piece 61 or 64 to obtain the result described and for moving certain of said parts into and out of cooperative relation. It also will be 20 understood that I have provided various adjusting means for bringing about an accurate operation of the parts in the timed relation referred to and for accurately bringing certain of said parts into cooperative relation. In addition to 25 this I have provided adjustable means for regulating the spring pressure, where necessary, of various of the springs employed such for example as the springs 51, 116 and 84.

Various changes may be made in the construction, and parts thereof employed without others, without departing from my invention as it is defined in the accompanying claims.

What I claim as new and desire to secure by Letters Patent is:

35 1. The combination of a cylindrical platen, flexible bands partly surrounding the platen and extending up beyond the printing line and effective for holding a work sheet introduced in the rear of the platen snugly against it and directing 40 such work sheet up past the printing line, a curved paper deflector beneath the platen movable towards and from the platen independently of said bands for receiving a work sheet introduced rearward into the machine from in front of and beneath the platen and into the space intermediate said bands and deflector, and a second 45 paper deflector movable across the printing line into and out of effective position and being when in effective position in cooperative relation with and forming substantially a continuation of said first 50 mentioned deflector to aid in the rearward introduction of a work sheet thereto.

55 2. The combination of a cylindrical platen, flexible bands partly surrounding the platen and extending from the rear thereof up and beyond the printing line and effective for holding a work sheet introduced in the rear of the platen snugly against it at the lower side and front thereof and directing such work sheet up past 60 the printing line, a curved paper deflector beneath the platen for receiving a work sheet introduced rearward into the machine from in front of and beneath the platen and into the space intermediate said bands and deflector, 65 means for effecting a movement of said deflector away from the platen to provide an enlarged space between the deflector and said bands for the ready introduction of said rearwardly introduced work sheet, a second paper deflector movable across the printing line into and out of effective position and being when in effective 70 position in cooperative relation with and forming substantially a continuation of said first mentioned deflector to aid in the rearward introduction of a work sheet thereto, and means for mov- 75

ing said second deflector to effective position when the first mentioned deflector is moved away from the platen and for moving the second deflector to ineffective position when said first mentioned deflector is moved towards the platen. 5

3. The combination of a cylindrical platen, flexible bands partly surrounding the platen and effective for holding a work sheet introduced in the rear of the platen snugly against it and directing such work sheet up past the printing line, a curved paper deflector beneath the platen for receiving a work sheet introduced rearward into the machine from in front of and beneath the platen and into the space intermediate said bands and deflector, means for effecting a movement of said deflector independently of said bands away from the platen to provide an enlarged space between said deflector and said bands for the ready introduction of said rearwardly introduced work sheet, a line indicator 20 separate and distinct from said deflector and shiftable to and from indicating position, and automatically operating means for shifting said indicator away from indicating position when said deflector is shifted away from the platen. 25

4. The combination of a cylindrical platen, flexible bands partly surrounding the platen and effective for holding a work sheet introduced in the rear of the platen snugly against it and directing such work sheet up past the printing line, a curved paper deflector beneath the platen for receiving a work sheet introduced rearward into the machine from in front of and beneath the platen and into the space intermediate said bands and deflector, paper feed rollers shiftable 30 to and from the platen, automatically operating means for shifting said deflector towards and from the platen depending on the movement of said feed rollers with reference to the platen, a line indicator shiftable to and from indicating 35 position, and means for shifting said indicator to indicating position when said feed rollers and deflector are moved towards the platen and for moving the indicator away from indicating position when said deflector and feed rollers are 40 moved away from the platen. 45

5. The combination of a platen, feed rollers movable to and away from the platen, means for thus moving the feed rollers and for placing them under spring pressure against the platen, a line indicator movable to and from indicating position, and means for moving said line indicator to indicating position as the feed rollers are moved to the platen and for moving the indicator away from indicating position as said feed rollers are placed under spring pressure against the platen. 55

6. The combination of a platen, feed rollers movable to and away from the platen, means for thus moving the feed rollers and for placing them under spring pressure against the platen, a line indicator movable to and from indicating position, means for moving said line indicator to indicating position as the feed rollers are moved to the platen and for moving the indicator away 60 from indicating position as said feed rollers are placed under spring pressure against the platen, a paper deflector mounted for movement towards and from the platen, and means for moving said paper deflector away from the platen when the feed rollers are moved away from the platen and for moving said deflector towards the platen when the feed rollers are moved towards the platen. 65

7. The combination of a platen, feed rollers 70

movable to and away from the platen, means for thus moving the feed rollers and for placing them under spring pressure against the platen, a line indicator movable to and from indicating position, means for moving said line indicator to indicating position as the feed rollers are moved to the platen and for moving the indicator away from indicating position as said feed rollers are placed under spring pressure against the platen, a curved paper table beneath the platen mounted for movement towards and away therefrom, a second paper deflector movable towards and from the front of the platen, and means for moving said first mentioned deflector towards the platen as said feed rollers are moved towards the platen and for moving the second deflector away from the platen as said feed rollers are moved towards the platen.

8. The combination of a platen, feed rollers movable to and away from the platen, controlling means for thus moving the feed rollers and for placing them under spring pressure against the platen, a line indicator movable to and from indicating position, means for moving said line indicator to indicating position as the feed rollers are moved to the platen and for moving the indicator away from indicating position as said feed rollers are placed under spring pressure against the platen, a curved paper table beneath the platen mounted for movement towards and away therefrom, a second paper deflector movable towards and from the front of the platen, means for moving said first mentioned deflector towards and the second deflector away from the platen as said feed rollers are moved towards the platen and for moving the first deflector away from and the second deflector towards the platen as said feed rollers are moved away from the platen, said controlling means including a hand actuated member, and latching means for locking said member at the end of its movement in one direction for holding said feed rollers applied to the platen with a spring force.

9. The combination of a platen, paper feed rollers cooperative therewith, and means for moving said feed rollers to and from the platen parallel with the axis thereof and for maintaining them spring pressed against the platen, said means including a manually controlled member, a rock shaft turned on its longitudinal axis by said manually controlled member, a spring intermediate said rock shaft and said feed rollers and which is placed under tension by a movement of said manually controlled member and rock shaft after the feed rollers reach the platen, and a latch for locking said manually controlled member against return movement under the reactive force of said spring.

10. The combination of a platen, paper feed rollers cooperative therewith, and means for moving said feed rollers to and from the platen parallel with the axis thereof and for maintaining them spring pressed against the platen, said means including a manually controlled member, a rock shaft turned on its longitudinal axis by said manually controlled member, a spring intermediate said rock shaft and said feed rollers and which is placed under tension by a movement of said manually controlled member and rock shaft after the feed rollers reach the platen, a latch for locking said manually controlled member against return movement under the reactive force of said spring, and means operable at will for releasing said latch and thereby relieving the spring pressure on the feed rollers

without moving the feed rollers away from the platen.

11. The combination of a platen, paper feed rollers mounted for shifting movement to and from the platen, a line indicator shiftable to and from indicating position, a finger piece for controlling the shifting movements of said feed rollers and indicator, and means for causing said rollers to move to the platen and the indicator to move to indicating position by a movement of said finger piece in one direction and for causing said indicator to move away from indicating position by a continued movement of said finger piece after the feed rollers reach the platen.

12. The combination of a platen, paper feed rollers mounted for shifting movement to and from the platen, a line indicator shiftable to and from indicating position, a finger piece for controlling the shifting movements of said feed rollers and indicator, means for causing said rollers to move to the platen and the indicator to move to indicating position by a movement of said finger piece in one direction and for causing said indicator to move away from indicating position by a continued movement of said finger piece after the feed rollers reach the platen, a spring, and means for applying the force of said spring to said feed rollers after the feed rollers reach the platen and by said continued movement of the finger piece.

13. The combination of a platen, paper feed rollers mounted for shifting movement to and from the platen, a line indicator shiftable to and from indicating position, a finger piece for controlling the shifting movements of said feed rollers and indicator, means for causing said rollers to move to the platen and the indicator to move to indicating position by a movement of said finger piece in one direction and for causing said indicator to move away from indicating position by a continued movement of said finger piece after the feed rollers reach the platen, a paper deflector mounted for movement towards and from the platen, and means controlled by an actuation of said finger piece for controlling the movement of said deflector.

14. The combination of a platen, paper feed rollers mounted for shifting movement to and from the platen, a line indicator shiftable to and from indicating position, a finger piece for controlling the shifting movements of said feed rollers and indicator, means for causing said rollers to move to the platen and the indicator to move to indicating position by a movement of said finger piece in one direction and for causing said indicator to move away from indicating position by a continued movement of said finger piece after the feed rollers reach the platen, a paper deflector shiftable across the printing line into and out of effective position, and means controlled by an actuation of said finger piece for shifting said deflector to effective position when the finger piece is moved to shift said feed rollers away from the platen.

15. The combination of a platen, paper feed rollers mounted for shifting movement to and from the platen, a line indicator shiftable to and from indicating position, a finger piece for controlling the shifting movements of said feed rollers and indicator, means for causing said rollers to move to the platen and the indicator to move to indicating position by a movement of said finger piece in one direction and for causing said indicator to move away from indicating position by a continued movement of said finger piece after the feed rollers reach the platen.

- sition by a continued movement of said finger piece after the feed rollers reach the platen, a paper deflector shiftable across the printing line into and out of effective position, means controlled by an actuation of said finger piece for shifting said deflector to effective position when the finger piece is moved to shift said feed rollers away from the platen, a second paper deflector arranged beneath the platen and mounted for shifting movement towards and from the platen, and means for moving said second deflector away from the platen when the feed rollers are moved away from the platen.
16. The combination of a cylindrical platen, a work sheet guiding and controlling means comprising a work sheet deflector movable to and from effective position across the printing and when in effective position aiding in directing a work sheet rearward and downward in front of and beneath the platen, and means for controlling such movements of the deflector comprising means for mounting the deflector to turn on two pivotal centers and for controlling its movement around such centers so that the deflector in its movement to effective position will first move bodily towards the platen and will then receive a downward movement substantially tangential to the platen at the front face thereof.
17. The combination of a cylindrical platen, paper feed rollers cooperative therewith, a rock shaft, arms on said rock shaft for carrying said feed rollers, a lost motion connection between said rock shaft and said arms, springs on said rock shaft each anchored at one end to the rock shaft and connected at the other end to one of said arms, and a finger piece for turning said rock shaft, whereby the feed rollers may be moved to and from the platen by a turning of said rock shaft free from the resistance of said springs and a continued movement of the finger piece after the feed rollers reach the platen will result in stressing said springs and applying the force thereof through said arms to the feed rollers.
18. The combination of a cylindrical platen, paper feed rollers cooperative therewith, a rock shaft, arms on said rock shaft for carrying said feed rollers, a lost motion connection between said rock shaft and said arms, springs on said rock shaft each anchored at one end to the rock shaft and connected at the other end to one of said arms, a finger piece for turning said rock shaft, whereby the feed rollers may be moved to and from the platen by a turning of said rock shaft free from the resistance of said springs and a continued movement of the finger piece after the feed rollers reach the platen will result in stressing said springs and applying the force thereof through said arms to the feed rollers, and a locking latch for locking said rock shaft against return movement under the reaction of said stressed springs.
19. The combination of a cylindrical platen, paper feed rollers cooperative therewith, a rock shaft, arms on said rock shaft for carrying said feed rollers, a lost motion connection between said rock shaft and said arms, springs on said rock shaft each anchored at one end to the rock shaft and connected at the other end to one of said arms, a finger piece for turning said rock shaft, whereby the feed rollers may be moved to and from the platen by a turning of said rock shaft free from the resistance of said springs and a continued movement of the finger piece after the feed rollers reach the platen will result in stressing said springs and applying the force thereof through said arms to the feed rollers, a second finger piece operatively connected to turn said shaft, and a latch that automatically functions on the operation of said second finger piece to hold the rock shaft against return movement under the reaction of said stressed springs, whereby the stressed springs may be locked in stressed condition or not depending on which of the two finger pieces is employed to turn the shaft and stress the springs.
20. The combination of a cylindrical platen, paper feed rollers cooperative therewith, a rock shaft, arms on said rock shaft for carrying said feed rollers, a lost motion connection between said rock shaft and said arms, springs on said rock shaft each anchored at one end with the aid of adjustable means to the rock shaft and connected at the other end to one of said arms, and a finger piece for turning said rock shaft, whereby the feed rollers may be moved to and from the platen by a turning of said rock shaft free from the resistance of said springs and a continued movement of the finger piece after the feed rollers reach the platen will result in stressing said springs and applying the force thereof through said arms to the feed rollers, the force thus exerted by said springs depending on the adjustment of said adjustable means.
21. The combination of a platen, feed rollers movable to and from the platen and adapted to be forced into contact therewith, a line indicator movable to and from indicating position, and automatically operating means for bringing about an upward movement of the line indicator from an ineffective position to a line indicating position as the feed rollers approach the platen and for lowering said indicator from the line indicating position as the feed rollers are forced against the platen.
22. The combination of a platen, feed rollers movable to and from the platen and adapted to be forced into contact therewith, a line indicator movable to and from indicating position, automatically operating means for bringing about an upward movement of the line indicator from an ineffective position to a line indicating position as the feed rollers approach the platen and for lowering said indicator from the line indicating position as the feed rollers are forced against the platen, and a paper deflector automatically moved into and out of effective position in timed relation to said paper feed rollers and line indicator.
23. The combination of a platen, feed rollers movable to and from the platen and adapted to be forced into contact therewith, a line indicator movable to and from indicating position, automatically operating means for bringing about an upward movement of the line indicator from an ineffective position to a line indicating position as the feed rollers approach the platen and for lowering said indicator from the line indicating position as the feed rollers are forced against the platen, a paper deflector beneath the platen movable towards and away therefrom, a second paper deflector movable to and from effective position in front of the platen and when in effective position aiding in directing a rearwardly introduced work sheet from the front of the platen to and beneath the same, and, means for automatically moving said deflectors in timed relation to said feed rollers and line indicator.
24. The combination of a cylindrical platen, paper feed rollers arranged above the printing line and movable to and from the platen, a paper

- table in the rear of the platen, means for directing work sheets introduced into the machine from the rear of the platen with the aid of said paper table beneath the platen and up past the printing line, a paper table at the front of and above the platen to aid in the rearward and downward introduction of work sheets from in front of the platen, and a paper deflector in front of the platen movable across the printing line into and out of effective position and when in effective position further aiding in the rearward introduction of work sheets received on the front paper table.
25. The combination of a cylindrical platen, paper feed rollers arranged above the printing line and movable to and from the platen, a paper table in the rear of the platen, means for directing work sheets introduced into the machine from the rear of the platen with the aid of said paper table beneath the platen and up past the printing line, a paper table at the front of and above the platen to aid in the rearward and downward introduction of work sheets from in front of the platen, a paper deflector in front of the platen movable across the printing line into and out of effective position and when in effective position further aiding in the rearward introduction of work sheets received on the front paper table, and automatically operating means for moving said paper deflector in timed relation to said paper feed rollers.
30. 26. The combination of a cylindrical platen, paper feed rollers arranged above the printing line and movable to and from the platen, a paper table in the rear of the platen, means for directing work sheets introduced into the machine from the rear of the platen with the aid of said paper table beneath the platen and up past the printing line, a paper table at and above the front of the platen to aid in the rearward and downward introduction of work sheets from in front of the platen, a paper deflector beneath the platen movable towards and away from it, a second paper deflector in front of the platen movable across the printing line into and out of cooperative relation with said first mentioned deflector, and automatically operating means for moving said deflectors in timed relation to said paper feed rollers.
27. The combination of a platen, feed rollers movable to and away from the platen and for placing them under spring pressure against the platen, a line indicator movable to and from indicating position, means for moving said line indicator to indicating position as the feed rollers are moved to the platen and for moving the indicator away from indicating position as said feed rollers are placed under spring pressure against the platen, a curved paper table beneath the platen mounted for movement towards and away therefrom, a second paper deflector movable towards and from the front of the platen, means for automatically controlling the movements of said deflectors in timed relation with the movement of said feed rollers, said last mentioned means including a hand actuated member, and latching means for locking said member at the end of its movement in one direction for holding said feed rollers applied to the platen with a spring force.
28. In a front strike typewriting machine, the combination of a cylindrical platen fixed against movement from printing position, flexible bands partly surrounding the platen and extending from the rear thereof up and beyond the printing line and effective for holding a work sheet introduced in the rear of the platen snugly against it at the lower side and front thereof and directing such work sheet up past the print line at the front of the platen, a curved paper deflector permanently maintained beneath the platen for receiving a work sheet introduced rearward into the machine from in front of and beneath the platen and into the space intermediate said bands and deflector, paper feed rollers shiftable at will to and from the platen independently of a movement of the latter, and automatically operating means for shifting said deflector towards and from the platen depending on the movement of said feed rollers with reference to the platen.
29. The combination of a platen, paper feed rollers mounted for movement parallel with the axis of the platen toward and from the surface thereof, a spring for said feed rollers which moves therewith in such movements, and means for moving said feed rollers to and from the platen free from the force of said spring and for stressing said spring and applying the force thereof against the feed rollers after they have reached the platen and been arrested thereby, said means including a rock shaft that turns on its longitudinal axis, and means that enable said rock shaft to continue its rocking movement to stress said spring after the feed rollers reach the platen.
30. The combination of a platen, paper feed rollers mounted for movement parallel with the axis of the platen to and from the surface thereof, a rock shaft on which said feed rollers are supported, a finger piece for rocking said shaft on its longitudinal axis, a spring interposed between said rock shaft and feed rollers and movable therewith without exerting a spring pressure on the feed rollers, and means that enable said finger piece and rock shaft to continue their movement after the feed rollers have been moved to and arrested by the platen and for causing said spring to be stressed by said continued movement of the finger piece and rock shaft and apply the force of the stressed spring to the feed rollers.

GEORGE JAMES MUNSON PILGRIM.
